(57) CLAIM

The ornamental design for a portion of a laundry appliance, as shown and described.

DESCRIPTION

FIG. 1 is a front perspective view of a portion of a laundry appliance showing our new design; and,

FIG. 2 is a front view thereof.

The broken line(s) which define the bounds of the claimed design form no part thereof. The broken line showing of portions of the laundry appliance is included for the purpose of illustrating environmental matter and forms no part of the claimed design.

1 Claim, 2 Drawing Sheets

FIG. 1

FIG. 2

UNITED STATES PATENT AND TRADEMARK OFFICE
CERTIFICATE OF CORRECTION

PATENT NO. : Des. 547,913 S
APPLICATION NO. : 29/246756
DATED : July 31, 2007
INVENTOR(S) : Reim et al.

It is certified that error appears in the above-identified patent and that said Letters Patent is hereby corrected as shown below:

Title page, Under DESCRIPTION the last sentence:

“The broken line showing of portions of the laundry appliance is included for the purpose for purpose of illustrating environmental matter and forms no part of the claimed design.”

has been replaced with

-- The broken line showing of unshaded portions of the laundry appliance is included for the purpose of illustrating environmental matter and forms no part of the claimed design.--
